(57) **CLAIM**

The ornamental design for a seat frame, as shown and described.

DESCRIPTION

FIG. 1 is a perspective view of a seat frame in accordance with the new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top view thereof;

FIG. 7 is a perspective view of an alternative embodiment of the seat frame;

FIG. 8 is a front elevational view thereof;

FIG. 9 is a right side elevational view thereof;

FIG. 10 is a left side elevational view thereof;

FIG. 11 is a rear elevational view thereof; and,

FIG. 12 is a top view thereof.

The broken lines in the figures are for illustrative purposes only and form no part of the claimed design.
